JOHN HADFIELD, JR., OF PHILADELPHIA, PENNSYLVANIA.

PROCESS FOR MAKING STOCKINGS.

Application filed March 5, 1920. Serial No. 363,450.

REISSUED

To all whom it may concern:

Be it known that I, JOHN HADFIELD, Jr., a citizen of the United States, residing in Philadelphia, Pennsylvania, have invented 5 certain Improvements in Processes for Making Stockings, of which the following is a specification.

My invention relates to improvements in stockings and processes for making the same, 10 and the object of my invention is to provide a new process for forming stockings of the type known as full fashioned, whereby a great saving is achieved both in time and in the cost of manufacture, and an article 15 of superior quality obtained.

With reference to the drawings:

Figure 1, illustrates a stocking made in accordance with my invention;

Fig. 2, shows the upper portion of the 20 stocking, the forming of which constitutes the first step in my process, and

Fig. 3, is a view of the upper portion of the stocking shown in Fig. 2, after it has been divided at the rear and is ready for 25 transference to the full fashioned knitting machine.

The present method of forming stockings of the type known as full fashioned is to knit the entire leg portion upon what is commonly known as a full fashioned stocking knitting machine. This is a comparatively lengthy process, due to the fact that in forming the welt, the upper portion of the stocking must be turned over by hand.

During the time that the welt is being formed, it is necessary that the machine upon which the stocking is being formed remain idle, and since the knitting and turning of the upper portion of the stocking consumes 30 substantially three-fourths of the time required to form the entire leg, it is apparent that the actual loss is considerable. All this will be fully understood and appreciated by those acquainted with the art.

I have discovered that by forming the upper portion of the leg of my stocking upon a circular stocking knitting machine of the type employed in the manufacture of so-called seamless hosiery, and transferring 40 this upper portion of the stocking from the seamless machine to the full fashioned machine for completion of the lower portion of the leg, I am able to obtain a considerable saving both in time and actual cost of manu-

facture, and at the same time put out an 55 article which is superior to the stocking formed entirely upon the full fashioned machine.

In carrying out my process, it is necessary, first, that the circular machine employed in 60 knitting the top of the stocking shall have the same number of needles as the full fashioned machine employed for knitting the lower portion of the leg, and that the two machines shall knit fabrics which are identical. This 65 can be easily arranged for. In following out the process, therefore, I first form upon the said circular knitting machine a tubular blank 1, such as shown in Fig. 2. This knitting machine, in forming the upper portion 70 of the stocking, automatically forms the welt 2, and after the blank is received from the machine, it is only necessary to divide the same at one side before it may be transferred to the full fashioned machine for the knitting 75 of the shaped lower portion 3 of the leg. In order to provide a guide for the operator who cuts the tubular blanks, a stitch may be dropped at one side, or longitudinal wale or other guide line formed, as indicated 80 in the drawings by the numeral 4. After the tubular blank has been opened, as shown in Fig. 3, it is ready to be transferred to the full fashioned knitting machine upon which the lower portion 3 of the leg is formed, and 85 a loose course or transfer line 5 formed in the blank constitutes a guide whereby the transfer may be swiftly and accurately made.

The upper portion of the stocking which 90 is formed upon the said circular machine is substantially similar to the corresponding upper portion of a stocking knitted upon the full fashioned machine, since all the shaping of the leg done upon a full fashioned machine is upon the lower portion 95 of the leg. The stocking therefore obtained by my process is, in the essential features, exactly similar to the stocking knitted wholly upon the full fashioned machine. There are, however, certain particulars in which a stocking made in accordance with my invention is superior to the ordinary full fashioned stocking. One of the main difficulties experienced in the manufacture 100 of seamless hosiery is the fact that in order to obtain proper relative proportions in the lower portion of the leg which lies around

the ankle and in the extreme upper portion of the leg, it is necessary to limit the circumference of the upper portion of the leg. If this upper portion of the leg is 5 made larger than is ordinarily the custom, the ankle must be correspondingly enlarged, and a stocking which bags around the ankle results. Even in full fashioned stockings of the usual type, there is as a rule in 10 sufficient provision made at this point, and the stockings are frequently found to bind the wearer at the top. It is, in fact, extremely hard to find a stocking which will meet all requirements, and a happy mean 15 is in most cases the best that can be re- ized. It is a fact, however, that although the circular knitting machine employed for forming the upper part of my stocking has the same number of needles as the full 20 fashioned machine which forms the lower portion thereof, and though the fabrics formed upon the two machines are apparently identical, yet the upper portion of the leg of a stocking made in accordance 25 with my invention has greater elasticity and can without strain encompass a greater area than a stocking knit in its entirety upon the full fashioned machine employed to form the lower portion of the leg of my stock- 30 ing. As a consequence, I obtain a stocking which is capable of wider application and more general use than the stocking formed complete upon the full fashioned machine.

35 If still further flexibility is required, moreover, it is possible upon the circular knitting machine to form the inside of the welt of a fabric less closely knit than that of the rest of the stocking, and this will 40 afford even greater flexibility to the welt while not detracting from the appearance of the stocking. Furthermore, in transferring the upper portion 1 of the stocking to the full fashioned machine, it is unnecessary to 45 slit the blank completely open, it being sufficient to slit the blank from the bottom up as far as the welt only, the welt being left intact. In this event, there will be found in my stocking an actually greater 50 number of stitches than in a full fashioned stocking, the leg of which is formed complete upon the full fashioned machine em- 55 ployed to knit the lower portion of the leg of my stocking, since in stitching up the back of the open blank, a number of stitches is of necessity sacrificed. Actually greater width may thus be obtained at the top of the stocking.

I am able, furthermore, in my stocking 60 to take advantage of the so-called lock stitch or anti-run-back, which is a stitch formable only upon circular machines such as I em- 65 ploy in forming the upper portion of my stocking. This lock stitch is placed some- where below the welt, as indicated in the

drawings by the numeral 6, the purpose being to prevent any runs which may start from injuries caused by a garter from ad- 70 vancing further down the leg than the posi- 75 tion of the said lock stitch. This is a de- cided advantage, particularly in silk hose, and the full fashioned stocking made in the usual manner is unable to include this fea- 80 ture. I am able, however, to form the said lock stitch in the upper portion of the 85 stocking which is formed upon the cir- 90 cular machine, and as a consequence, it is incorporated in my completed full fashioned stocking.

Many other possible advantageous fea- 80 tures will present themselves to those ac- 95 quainted with the art.

As indicative of the great saving of time resulting from my process, I am able to form the leg of my stocking complete in 85 approximately one-third of the time that it takes to form the leg of a stocking upon a full fashioned machine, this saving con- 90 stituting the difference in the time that it takes to form the upper portion of the 95 stocking upon the respective machines. I am also able to avoid in the formation of my stocking considerable close and arduous work upon the part of the operator, and the machine-formed welt is generally of su- 100 perior quality to the welt formed manually upon the full fashioned machine.

Aside from the actual saving in time and labor thus described, I am able to operate my machines practically continuously, with- 100 out the necessity for keeping them idle for protracted periods, and the production is thereby greatly increased, this actual in- 105 crease of production being approximately 200%. In fact, I obtain this greatly in- creased production at an actual cost of manufacture which is less per article than 110 in the ordinary process of manufacture.

Since the seamless knitting machines are 110 comparatively cheap and easy to obtain, my process will particularly recommend itself to manufacturers desiring to increase their production while being unable or unwilling to go to the expense of purchasing more of the full fashioned machinery.

I claim:

1. The method of producing fashioned hosiery, which comprises forming the upper portion of the leg as a tubular web having a longitudinal slit, laying out the lower sec- 115 tion of the said web in a substantially straight line, and continuing the leg as a flat web from said lower section.

2. The method of forming fashioned hosiery, which comprises knitting the upper portion of the leg as a continuous tubular web, cutting the web to permit the laying out of the lower section thereof in a substan- 120 tially straight line, and continuing the leg as a flat web from the said lower section.

3. The method of forming fashioned hosiery, which comprises knitting the upper portion of the leg including the welt as a continuous tubular web, cutting the web to permit the laying out of the lower section thereof in a substantially straight line, and continuing the leg as a flat web from the said lower section.
4. The method of forming fashioned hosiery, which comprises knitting the upper portion of the leg including the welt as a continuous tubular web, cutting the web to permit laying out of the lower section thereof in a substantially straight line, continuing the leg from the said lower sec-
- tion as a flat web, and joining the edges of the fabric to form the finished leg.
5. The method of forming fashioned hosiery, which consists in knitting the upper portion of the leg including the welt as a continuous tubular web, cutting the web to permit laying out the lower section in a substantially straight line, continuing the knitting of the remainder of the stocking from the said lower section as a flat web, 25 and stitching the edges of the said latter web and the divided portion of the tubular web to complete the stocking.

JOHN HADFIELD, JR.
